UNITED STATES PATENT OFFICE

HAROLD D. BOSE, OF VALLEY STREAM, NEW YORK, ASSIGNOR TO MODEL BRASSIERE CO. INC., OF NEW YORK, N. Y., A CORPORATION OF NEW YORK

BRASSIERE

Application filed July 22, 1932. Serial No. 623,961.

This invention relates to brassières and has for its object to provide a new and improved garment of the type shown in United States Letters Patent to McKeefrey, No. 1,590,693, dated June 29, 1926, the particular object of my invention being to make a garment of this type adjustable to a number of wearers to all of whom garments of a certain size are adapted but whose bust location and widths are different.

In the accompanying drawings which illustrates two examples of my invention without, however, defining its limits, Fig. 1 is a rear view of one form of my novel brassière; Fig. 2 is a side view of Fig. 1; Fig. 3 is an enlarged fragmentary view showing an adjustable feature of the garment; Fig. 4 is a rear view of another form of my novel brassière; and Figs. 5 and 6 are enlarged fragmentary views showing other positions of the adjustable feature illustrated in Fig. 3.

In the form illustrated in Figs. 1 and 2, the brassière comprises an outer section 10 of relatively soft fabric or other equally pliable material, provided with two bust-receiving pouches 18, 18, formed of a similarly soft or pliable fabric. The upper edge of each pouch is curved along at least a portion thereof as shown at *h*. Suitable fastening devices, such as a hook 11 and eye 12, permit the garment to be fastened about the body of the wearer. The pouches 18, 18 are united at their lower, and a portion of their upper, edges to the outer section 10 by stitches preferably passing through binding tapes 13, 13 which in turn may, if desired, be covered by strips of lace material 13a. The outer section 10 may, if desired, be given shape by darts 14, 14. The two pouches 18, 18 are further united to the outer section 10 by means of two or more lines of stitches 17, preferably passing through a strip of material 25 and securing the same in place on the garment, thus forming two or more parallel pockets in which tapes 26 are located in such a manner that upon proper manipulation thereof the garment may be adjustably gathered in a vertical direction.

Insofar as hereinabove described, the features of the brassière are not novel with me

but are substantially as shown in the Letters Patent to McKeefrey hereinabove referred to and are therefore not described in further detail.

A supporting band 30 is united by its two ends to the upper edge of the left-hand pouch piece 18, the ends being secured preferably at the ends of the curved portion *h*. In practice it is advisable to make the band 30 of two separate pieces united at a slight angle to each other so as to aid in a smooth encircling of the bust. Preferably this band is made of elastic material so as to enable it to afford more ready adjustment and also to suspend the pouch 18 in a yielding manner, and the band is long enough to enable it, in conjunction with the upper edge portion *h*, to encircle the bust of the wearer. To approximately the central portion of the band 30 there is secured in any suitable manner one end of a connecting strip 21 whose other end is secured to the upper edge of the section 10 and passes through a slotted member 22. This member is provided preferably with two slots through the lower one of which, 22a, the connecting piece 21 passes. To the upper end of such slotted member there is fastened one end of a shoulder strap 23, for instance by having the end pass through slot 22b and then sewed back onto the main body of the strap. By means of this slotted member the shoulder strap is slidably secured to the connecting piece; obviously the shoulder strap may be slidably secured to the connecting piece by any suitable means. The other end of the shoulder strap 23 is secured to the upper edge of the brassière near the left-hand edge thereof, as at 24. The connecting piece 21 is preferably made of non-elastic material, as shown for instance in Fig. 1, but may, if desired, be made of elastic material, as shown in Fig. 3.

The right-hand pouch piece 18 is provided with a supporting band 30, connecting piece 21, slotted member 22 and shoulder strap 23 in like manner.

In the form illustrated in Fig. 4, the brassière comprises, in addition to the bust supporting members, being the elements hereinabove described, a form shaping structure 100

consisting of front panel members 31, 31 and rear panel members 32, 32. Elastic gussets 33, 33 may be provided if desired between each adjoining pair of members 31, 32, and the members 32, 32 are provided with the usual fastening devices 34. The pouch members 18a do not extend, as in the structure shown in Fig. 1, to the outermost ends respectively of the brassière, but are preferably confined to the front panels 31, 31, the edge 13b thus extending upwardly to meet the upper edge 13c.

The advantages of my invention are more clearly apparent in the structure shown in Fig. 4 because the position of the panel portions on the person of the wearer is dictated by considerations other than those of the location of the busts, whereas the structure shown in Fig. 1 (frequently termed a bandreau) may be adjusted upwardly or downwardly with sole consideration to the location of the busts.

In the manufacture of brassières in large quantities for the market it is obviously necessary to make the garment of different sizes so as to fit wearers of different chest measurements. According to my invention a brassière of a given size, i. e. given chest measurement, may be adapted to fit any one of a number of wearers having the same chest measurement but having different bust locations. Busts may be located in the so-called "normal" position and may be the so-called "normal" distance from one another ("normal" width), or may be located at a higher or a lower than "normal" position or may be further apart or nearer together than the "normal" distance.

With the aid of my invention a brassière may readily be adjusted or, rather, adjust itself, to busts of these various locations and widths. The brassière may, for instance, be constructed so that when the adjustable means are in median position, the garment will fit, without a substantial degree of adjustment, busts of normal width and, more particularly in the case of the brassière shown in Fig. 4, busts of normal location. If the busts are further apart than the normal width, the inner portions of bands 30 will be stretched more than the outer portions, and the connecting piece will then assume the position somewhat as shown in Fig. 4; if the busts are of less than normal width the outer portions of the band 30 will stretch more than the inner portions and the connecting piece will then assume the position somewhat as shown in Fig. 1. In the case of normal position and width the connecting piece will assume the position somewhat as shown in Fig. 3. If the busts are higher than normal, the band 30 will be stretched and the connecting piece 21 will slide through slot 22a in the direction of the upper edge of the brassière so as to assume a position some-

what as shown in Fig. 6; when the location is lower than normal, the opposite will occur and the relation of the parts will be somewhat as shown in Fig. 5. These typical relationships of the parts serve to indicate how my brassière can adjust itself to busts of various locations and widths.

It would be possible to make the band 30 of non-elastic material but I much prefer to make it of elastic material to prevent distortion of the garment by exerting pulls on portions thereof which might better be taken up by an elastic material.

I claim:

1. A brassière adapted to encircle the body of the wearer in the bust region, comprising an outer section of pliable material, fastening means for securing the same in place on the body of the wearer, bust supporting pouches, located upon the inside of the said outer section and extending in opposite directions, said pouches opening upwardly to receive the busts, and supporting devices each of which comprises a band whose ends are fastened to the upper edge of a pouch at a distance sufficient to enable said upper edge and said band to encircle the bust, a connecting piece uniting the central portion of said strap to the upper edge of the outer section, a shoulder strap, one end of which is secured to the upper edge of the brassière near its outermost end, and means for securing the other end thereof slidably to said connecting piece.

2. A brassière in accordance with claim 1 in which the bands are made of elastic material.

HAROLD D. ROSE.
